UNITED STATES PATENT OFFICE

146,841

DESIGN FOR A VACUUM CLEANER

Russell J. Wolfe, Buffalo, N. Y.

Application June 29, 1946, Serial No. 131,184

Term of patent 7 years

(CL. D9—2)

To all whom it may concern:

Be it known that I, Russell J. Wolfe, a citizen of the United States, residing at Buffalo, in the county of Erie and State of New York, have invented a new, original, and ornamental Design for a Vacuum Cleaner, of which the following is a specification, reference being had to the accompanying drawing, forming a part thereof.

Fig. 1 is a side elevational view of a vacuum cleaner, showing my new design;

Fig. 2 is a top plan view; and

Fig. 3 is a front elevational view.

I claim:

The ornamental design for a vacuum cleaner, as shown.

RUSSELL J. WOLFE.
